UNITED STATES PATENT OFFICE

158,606

TEETHING DEVICE FOR BABIES

Martin H. J. McCloskey and Adam P. Neil,
Irvington, N. J.

Application August 10, 1949, Serial No. 4,390

Term of patent 7 years

(Cl. D83—11)

To all whom it may concern:

Be it known that we, Martin H. J. McCloskey, a citizen of the United States, residing in Irvington, county of Essex, and State of New Jersey, and Adam P. Neil, a citizen of the United States, residing in Irvington, county of Essex, and State of New Jersey, have invented a new, original, and ornamental Design for a Teething Device for Babies, of which the following is a specification, reference being had to the accompanying drawing, forming part thereof.

In the drawing:

Figure 1 is a front view of a teething device for babies, showing our new design;
Figure 2 is a side view thereof;

Figure 3 is a rear view thereof.

We claim:

The ornamental design for a teething device for babies, as shown.

MARTIN H. J. McCLOSKEY.
ADAM P. NEIL.
